UNITED STATES PATENT OFFICE

98,632

DESIGN FOR A SHOE

Samuel Winer, Haverhill, Mass.

Application January 4, 1936, Serial No. 60,413

Term of patent 3½ years

To all whom it may concern:

Be it known that I, Samuel Winer, a citizen of the United States of America, residing in Haverhill, Mass., county of Essex, and State of Mass., have invented a new, original, and ornamental Design for a Shoe, of which the following is a specification, reference being had to the accompanying drawing, forming part thereof,

I claim:

The ornamental design for a shoe substantially as shown.

SAMUEL WINER.
